Design for a Furnace

Design

15-890

Fig. 1

Fig. 2

John S. Brown,
Hartford Conn.
Act. May 26, 1857.

Patented May 26, 1857.

U.S. 890

Willis S. Bronson, of Hartford, Conn:
Letters Patent, No. 890, Dated May 26th. 1857.

The schedule referred to in these Letters Patent and making part of the same.

To all whom it may concern:

Be it known that I, Willis S. Bronson, of Hartford, County of Hartford, and State of Connecticut, have invented or produced a new and original shape and configuration of the several parts of a Hot Air Furnace; And I do hereby declare that the following is a full and exact description of the same, reference being had to the drawings in which the same letters indicate like parts in each of the figures.

Hes. 890

20

Fig: 1. is a perspective view.

Fig: 1. is a perspective view.
Fig: 2. shows a detached portion of the circulating

draft flues.

draft flues. A. is the body of the firepot, made broader at the base than at the upper portion near the commencement of the curved portion so as to allow of a free and easy draft to the pattern.

B, shows the conjugating projecting flues or radiators cast upon the body of the fire pot A. and are separated from the fire surface by inserting division plates in such a manner as to fill up the opening between the flues and the fire pot except what is necessary for draft. The flues which receive the conducting

K. I. D. are flanges which receive the conducting

pipes. P_1 are the vertical side pipes. N , the horizontal cross pipe. P_2 , the rod by which the damper is turned to regulate the draft.

R, the rod by which the clamps are turned to engage and release the jaws.

M, shows the hot air pipe which passes through the inner and rear portion of the fire surface. F, is the front plate. G, the fluing sides to the front plate. H, is the door opening into the firepot. I, is the door opening into the ash pit. S, is the exit pipe.

door opening into the ash pit. S. is the exha. pipe.
What I claim and desire to secure by Letters
Patent is, The shape and configuration of the several parts of the
A.M. said furnace as hereinabove described and shown in the drawings.
